UNITED STATES PATENT OFFICE.

WILLIAM R. BAKER, OF CHICAGO, ILLINOIS.

IMPROVEMENT IN METERS.

Specification forming part of Letters Patent No. 159,143, dated January 26, 1875; application filed December 14, 1874.

To all whom it may concern:

Be it known that I, WILLIAM R. BAKER, of Chicago, in the county of Cook and State of Illinois, have invented certain new and useful Improvements in Meters, of which the following is a specification:

My invention relates to that class of meters which are adapted to the measurement of fluids, such as gas and water, or other liquids.

The improvements claimed will hereinafter be set forth.

In the accompanying drawings, I have shown an apparatus embodying all my improvements. Obviously some of them might be used without the others, and the details of construction be modified in some respects without departing from my invention.

Figure 1 is a view, partly in elevation and partly in section, with portions of the casing and cylinder broken away, and Fig. 2 a plan view, partly in section, with the top of the casing removed.

A tight metallic case, A, is constructed with a removable portion—in this instance one side—to allow access to the interior of the casing. A cylinder, B, is mounted in the casing. The heads b b' are detachably secured in place, in this instance, by means of through-bolts C passing through the flanges of the heads and nuts c. Induction-pipes D D', connected with the supply-pipe or reservoir containing the fluid or liquid to be measured, enter the casing and lead into the cylinder through its heads. Eduction-pipes E E' lead from the cylinder by the sides of the inlet-pipes D D'.

These inlet and outlet pipes are shown, in this instance, as entering the cylinder in pairs at its ends, one inlet and one outlet pipe communicating with the cylinder at either end through a single pipe, near the bottom of the cylinder. In Fig. 2 these forked pipes are shown in plan and in section.

A piston-head, F, is fitted in the cylinder B, and has an annular groove in its periphery, as usual, for packing. The piston-rod F' passes through the cylinder-head b, and has fixed on its outer end an arm, f. The free end of this arm is provided with a pin on its inner side, which works in a guideway, f', supported in the casing in any suitable way, as the piston reciprocates. Cylindrical valves

or cocks G G', similar in general construction, work in the forked pipes constituting the inlet-pipes D D' and outlet-pipes E E'. Each of these valves is provided with two ways or openings, g g', at right angles to each other, those of G' being shown in Fig. 2 in section. The opening g is in the inlet-pipe, and the other, g', in the outlet-pipe. The openings or ways of the valve G are the reverse of those in G', the inlet-opening g in G being at right angles to the corresponding way in G', and the outlet-opening g' in the valve G at right angles to the outlet-opening in the valve G'.

By this construction, when the valves are moved simultaneously in the same direction, they are shifted so that the outlet-opening at one end and the inlet-opening at the other end of the cylinder, are brought in line with their pipes to open communication from the cylinder at one end, and to it at the other, the outlet and inlet ways opened by the movement of the valves being the ones previously closed; and as the opening of the inlet-way in either valve closes the outlet way of the valve, it is impossible to have two inlet or two outlet pipes communicating with the cylinder at the same time, or to open both ways in one valve at the same time.

To operate the valves together, they are provided with cranks H H', the wrists h h' of which are pivoted to the opposite ends of parallel bars, which constitute a guideway, I, for an oscillating lever, J, which acts first on one end and then on the other end of the guideway as it works in it, rocking the valves first to one side and then to the other simultaneously.

Instead of parallel bars, a single slotted or grooved bar might be used for this guideway I.

The oscillating lever J is pivoted at its lower end to a support, J', suitably fixed to the casing, while its upper or free end is controlled in its movements by the valve-connecting guideway I. A rod, K, is pivoted at one end to the lever J, as at k, and its opposite end has a slot, K', in which works a pin, k', on the end of the arm f, fast to the piston-rod. A lever, L, is pivoted at one end, as at l, to a support or projection of the casing, and has a weight, L', attached to its opposite end.

A spring, secured at one end to the lever and at the other to the casing, might be substituted for the weight.

The lever, it will be seen by reference to Fig. 1, is provided with a projection or point, l' , on its under side or edge, and is curved on both sides of this point. A roller, M , secured in the slotted lower end of the lever J , works against the under side of the vibrating lever L as the lever J oscillates on its pivot. The slot in the lever J serves as a guide to prevent displacement of the lever L . A pawl, N , pivoted to the lower part of the oscillating lever, engages with a ratchet-wheel, O , turning on or with a stud or spindle in the support J' . As the lever oscillates its pawl moves the wheel by means of the ratchet-teeth, and by a suitable train of gearing, outside the casing, connected with the spindle of the ratchet-wheel, (which might pass through the side of the case in a suitable stuffing-box,) registers the amount of liquid or fluid passed through the cylinder, its capacity being known.

In operation, the parts being in the position shown in Fig. 1, the water, gas, or other substance enters the measuring-cylinder by the induction-pipe D' , through the way g in the valve G' , and by its pressure moves the piston F toward the opposite end of the cylinder, forcing out, (if the meter has previously been in operation,) through the eduction-pipe E , whose way is open, and the way in the inlet D closed, the contents of the previously-filled cylinder, which empties into the casing. Slightly before or at the time the piston completes its stroke, the roller on the oscillating lever comes under and passes the curved-sided point l' on the vibrating lever L , and the valve-connecting guide I is quickly moved to the extent of its play—which may be limited by stops $p p'$ on the cylinder-heads $b b$ —in one direction by the end of the oscillating lever coming in contact with the end of its guideway I , the first movement being imparted to the oscillating lever by the piston through its rod, the arm f , and the slotted rod K connecting the oscillating lever and the arm f . The quick movement thus imparted to the valve-connecting guideway I , by the weighted vibrating lever L , acting, by its curved-pointed under side, on the oscillating lever, instantly reverses the positions of the valves $G G'$, opening the outlet E' and inlet D , and closing the outlet E and inlet D' . The contents of the cylinder, which was filled at one end as it

emptied at the other, now flow from E' , and the piston is moved to force out the contents of the cylinder before it, by the entrance of the gas or water under pressure at D , and the above-described operation is repeated indefinitely.

As the lever J oscillates, the quantity of gas, water, &c., which passes through the cylinder is registered through the ratchet and pawl, and suitable indicating mechanism on the outside of the casing. A pipe, P , leading from the casing, connects with suitable service or distributing pipes, by which to conduct the contents of the case to the desired points.

For measuring liquids the case should have an air-chamber to insure a constant flow from the pipe P during the operation of the meter.

The slot in the arm K admits of the quick movement of the valve-connecting bars or guide I , to shift the valves at the end of the piston's stroke, and prevents any undue strain on the arm f or its pin k' , upon which the slot slides, leaving the pin in the proper position, after shifting the valves, first at or near one end of the slot, and then at or near the other end, to act on the levers on the return stroke of the piston.

I claim as my invention—

1. The combination, with a measuring-cylinder, of forked pipes at its ends, constituting inlet and outlet pipes, two-way valves working in said pipes, and the connected valve-cranks, substantially as and for the purpose set forth.

2. The combination of the casing, the cylinder, the piston, the piston-rod, the inlet-pipes, the outlet-pipes, their valves, the valve-connecting guideway, and the oscillating lever working in the guideway to shift the valves, these members being constructed and operating substantially as set forth.

3. The combination of the valve-connecting guideway, the oscillating lever working therein, the piston-rod, the slotted rod pivoted to the oscillating lever and worked by the piston-rod, and the vibrating weighted lever, these members being constructed and operating substantially as set forth.

In testimony whereof I have hereunto subscribed my name.

WM. R. BAKER.
